US0D1110300S

(12) **United States Design Patent** (10) **Patent No.:** **US D1,110,300 S**
(45) **Date of Patent:** ** *Jan. 27, 2026

(54) **COMBINED WIRELESS CHARGER AND SPEAKER DOCK**

(71) Applicant: **Jim Hu**, Plano, TX (US)

(72) Inventor: **Jim Hu**, Plano, TX (US)

(73) Assignee: **Jim Hu**, Plano, TX (US)

(*) Notice: This patent is subject to a terminal disclaimer.

(**) Term: **15 Years**

(21) Appl. No.: **29/784,362**

(22) Filed: **May 19, 2021**

(51) **LOC (15) Cl.** **13-02**

(52) **U.S. Cl.**

USPC **D13/107**; D13/108
